WEARING APPAREL SUPPORTER

Earl B. French, Bridgeport, Conn., assignor to
The Union Specialty Company, Bridgeport,
Conn., a corporation of Connecticut

Application December 21, 1933, Serial No. 703,421

3 Claims. (Cl. 241—6)

The present invention relates to improvements in wearing apparel supporters, and particularly men's hose supporters, although it will be understood that the invention may be employed in supporters for other apparel than men's hose. An object is to provide a supporter which will effectually support the hose, and at the same time will be comfortable, will not slip out of its proper supporting position, and will not apply injurious or painful pressure on the leg. It is a further object to provide a supporter in which a pad-like structure is provided above the clasp which engages the wearer's body in self-conforming relation to the contour of the body over a relatively large area. Another object is to provide a supporter which when not in use will be in the form of a straight elastic band having parallel edges.

A further object is to provide a supporter which is of very simple and inexpensive construction, will be attractive in appearance, and will be long wearing.

With the above and other objects in view an embodiment of the invention is shown in the accompanying drawing, and this embodiment will be hereinafter more fully described with reference thereto, and the invention will be finally pointed out in the claims.

In the drawing:—

Fig. 1 is an elevation of a garter embodying my invention, the same being shown in its flat position when not in use.

Fig. 2 is an edge view.

Fig. 3 is a sectional view taken along the line 3—3 of Fig. 1.

Fig. 4 is an elevation of a portion of the webbing employed.

Fig. 5 is a plan view of the clasp attaching member employed.

Fig. 6 is a perspective view showing the garter in use.

Similar reference characters indicate corresponding parts throughout the several figures of the drawing.

Referring to the drawing, the wearing apparel supporter, according to the exemplary illustrated embodiment of the invention shown therein, comprises a relatively wide band 10 of longitudinally elastic webbing provided with a longitudinal slot 11 disposed substantially centrally between the longitudinal edges, this slot in the usual size garter being approximately two inches long in the unstretched state. The slot is preferably woven into the webbing in which case the reinforcing edge stitching 12 is also woven

by well known methods. If desired, however, it may be cut in plain webbing, and the edge reinforced as by button-hole stitching.

One end of the webbing is threaded through a loop member 13 and secured to a slide buckle 14, which is adapted to adjust the length of the webbing in the usual manner. At the other end a tab 15, of leather or the like, is folded about the end and secured by stitching 16, and a button member 17 for engagement by the loop member 13 is secured thereon, as by sewing 18.

A tab 19, which in its flat unattached relation is of substantially hour-glass shape, as shown in Fig. 5, is inserted through the slot 11 and folded about the central portion of the lower edge, its depending ends, which extend below the lower edge of the webbing, being engaged about the upper end of a hose-attaching clasp 20 and being secured by marginal stitching 21, which passes through the two sides of the tab 19 and through the webbing. The stitching securing the webbing follows the upwardly converging edges of the tab, and in the position of the garter on the leg, with the tab pulled down, this stitching is substantially at a right angle to the downwardly drawn portions of the webbing, so that there is a direct straight line pull on these portions and they lie flat upon the leg without bulges or wrinkles.

The supporter according to my invention will engage about the leg as a continuous band the upper portion above the slot 11 remaining straight, while the lower portion is drawn down to form a pad which lies smoothly over a relatively large area of the leg, so that it does not cut into the flesh. The upper straight portion it will be observed is not stretched to as great an extent as the lower portion so that there is comparatively little tension about the leg, and as the pull of the drawn down portions is transmitted to the rear there will be a comfortable and effectual support of the hose without any tendency to displace the garter either in an up and down direction or by twisting about the leg.

I have illustrated and described a preferred and satisfactory embodiment of the invention, but it will be obvious that changes may be made therein within the spirit and scope thereof, as defined in the appended claims.

Having thus described my invention, what I claim and desire to secure by Letters Patent is:—

1. A wearing apparel supporter comprising a flat strip of elastic material having a longitudinally extending slot forming a relatively narrow elastic upper strip portion above said slot longi-

- tudinally continuous with the remainder of said strip and a relatively narrow elastic lower strip portion below said slot also longitudinally continuous with the remainder of said strip and normally of the same length as said upper strip portion, and a wearing apparel securing tab secured centrally to said lower strip portion and disposed at a substantial distance from the ends of said slot and depending from the lower edge of said portion and being free of said upper strip portion whereby downward pull on said tab elongates said lower strip portion at each side of said tab to form said upper and lower strip portions into substantially triangular form.
15. 2. A wearing apparel supporter comprising a flat strip of elastic material having a longitudinally extending slot, forming a relatively narrow elastic upper strip portion above said slot longitudinally continuous with the remainder of said strip and a relatively narrow elastic lower strip portion below said slot also longitudinally continuous with the remainder of said strip, a wearing apparel securing tab folded over said lower strip portion and depending from the lower edge 20 of said portion, the fold being within said slot and the tab being disposed at each side of said portion, and securing means extending through each side of said tab and through said strip portion.

3. A wearing apparel supporter comprising a flat strip of elastic material having a longitudinally extending slot, forming a relatively narrow elastic upper strip portion above said slot longitudinally continuous with the remainder of said strip and a relatively narrow elastic lower strip portion below said slot also longitudinally continuous with the remainder of said strip and normally of the same length as said upper strip portion, and a wearing apparel securing tab secured centrally to said lower strip portion and disposed at a substantial distance from the ends of said slot and depending from the lower edge of said portion, and being free of said upper strip portion whereby downward pull on said tab elongates said lower strip portion at each side of said tab to form said upper and lower strip portions into substantially triangular form, the upper edge of said tab being contiguous to said slot and the side edges between the slot and the lower edge of said strip portion being inclined downwardly and outwardly and whereby said side edges are substantially at right angles to the longitudinal edges of the portions of said lower strip portion at the respective sides of said tab in said downwardly pulled relation of said tab.

EARL B. FRENCH.
